UNITED STATES PATENT OFFICE.

WILLIAM C. GREGG, OF HONOLULU, HAWAII.

STEAM-PLOW.

SPECIFICATION forming part of Letters Patent No. 638,921, dated December 12, 1899.

Application filed December 8, 1898. Serial No. 698,634. (No model.)

To all whom it may concern:

Be it known that I, WILLIAM C. GREGG, a citizen of the United States, residing at Honolulu, Island of Oahu, Hawaii, have invented 5 a new and useful Improvement in Steam-Plows, of which the following is a full, clear, and exact description, reference being made to the accompanying drawings, which form a part of this specification, and to the letters of 10 reference thereon.

My invention relates to agricultural implements; and it consists of a reversible or double-action gang-plow adapted to be drawn or driven backward and forward across the field, 15 so constructed that it will turn and lay the furrows evenly and in the same direction.

To this end my invention consists of a strong frame mounted upon wheels, thus forming a truck adapted to being drawn by a 20 cable or rope in either direction and avoiding the necessity of turning it around at the end of the furrows. To this truck is adjustably affixed a number of plows, (preferably eight,) one half of which are adapted to run 25 in one direction and the other half of which are adapted to run in an opposite direction, each group being located on a line diagonal to the frame and tangential to the furrows to be plowed, to the end that each plow shall 30 follow another, thereby laying the furrows, each in turn, in the bed of the one first preceding it. These groups of plows are alternately raised and lowered, according to the 35 direction in which my truck is being drawn or propelled, so that but one group is in use at one and the same time.

It further consists in providing means for raising or lowering an entire group of plows simultaneously, thereby effecting a saving in 40 time.

It still further consists in providing my truck with two pilot plows or excavators set directly in line with the wheels on one side of my truck, which two are pointed (like the 45 other plows) in opposite directions. The purpose of these is to remove obstructions and to smooth a path for the said wheels.

My invention is fully illustrated in the accompanying drawings, in which—

50 Figure 1 is a top view of my improved gang-plow; Fig. 2, a side elevation of one of the plows detached; Fig. 3, a front view of the

same, and Fig. 4 a side elevation of the endless screw or worm-gear which forms a part of the means employed in raising and lowering my plows in the frame. 55

Similar letters refer to similar parts throughout the several views.

A is the truck; B, the plows; C, the adjusting mechanism, and D the pilot-plows. 60

The truck A consists of the frame *a* and the wheels *b*. The frame *a* may be made of any desired form and of any suitable material, iron being best adapted to the purpose. The wheels *b*, (preferably four in number,) upon 65 which the frame is mounted, are of ordinary construction, and hence need no description herein. To the frame *a* the standards of the several plows are adjustably secured in such manner as to admit of their being raised or 70 lowered at will. These standards are provided with lateral cogs *c*, thus forming a "rock," the teeth of which engage those of pinions *e* of the adjusting mechanism C.

The plows B are not unlike those commonly 75 used, and hence need no description. They are arranged in such order that one group *B'*, diagonally arranged in the frame, are adapted to run in one direction and the other group *B''*, also diagonally arranged in the frame, 80 are adapted to run in an opposite direction.

The adjusting mechanism C consists of the horizontal diagonal shafts *d*, the pinions *e*, driven thereby, the gear-wheel *f*, mounted thereon, the vertical shaft *g*, and the hand-wheel *h*. The shafts *g* are journaled in the boxes within which they revolve. The pinions *e* are rigidly affixed to and revoluble with the shafts *d*. The gear-wheels *f* are securely keyed or otherwise secured to and revolve the 90 shafts *d*. The vertical shafts *g* are journaled in the frame A. They are provided with spiral threads which engage the teeth of the gear-wheels *f*. The hand-wheels *h* serve to impart horizontal rotary motion to the vertical shafts *g*, the spiral threads of which in turn impart vertical rotary motion to the gear-wheels *f*, which rotate the horizontal shafts *d* and with them the pinions *e*, the teeth of 95 which engage those of the plow-standards, thereby raising or lowering them, as desired. 100

The pilot-plows D are set directly in front of the "land-wheels" of my plow and serve, as before stated, to remove obstructions and

to smooth the paths in either direction for the wheels *b*.

5 *jj* are sections of the cable used in drawing my plow backward and forward across the field, power being supplied to it by steam-engines suitably located to wind and unwind the same.

10 It is apparent that power may be applied to the gear-wheel *f* instead of using the hand-wheel shown, if so desired.

15 In practice I run my plow across one end of a field, plowing four furrows, (more when more plows are employed,) all the furrows being turned in the same direction and each laid in the bed of the one next preceding it. Then when at the end of the furrows I lower one group of plows and raise another group through the use of the adjusting mechanism shown and in the manner above described, 20 when the plow is drawn in an opposite direction and the reversely-arranged plows will turn four more furrows, and thus I proceed until the land is all plowed.

Having thus described my invention, what 25 I claim, and desire to secure by Letters Patent, is—

1. In a steam-plow, the combination with a truck, of two gangs of plows reversely diagonally set in the frame of said truck, all of said

30 plows being vertically adjustable in the said frame, each gang being operated by independent mechanism, to the end, that one gang may be lowered to plow in one direction and the other gang lowered to plow in an opposite direction; means for alternately lowering and 35 raising each of the said gangs of plows, which means consist of hand-wheels, endless screws or worm-gears, shafts rotated thereby, pinions mounted upon the said shafts, the teeth of which engage the teeth of the plow-standards, 40 all substantially as shown and described.

2. In a steam-plow, the combination of a truck adapted to being drawn in opposite directions, said truck consisting of a suitable frame mounted upon wheels, plows vertically 45 adjustable in said frame, and means for lowering and raising the same, and reversely-arranged pilot-plows or excavators affixed in the front and rear of the wheels on said truck, all substantially as shown and described. 50

In testimony whereof I have hereunto signed my name this 3d day of December, A. D. 1898.

WILLIAM C. GREGG.
